UNITED STATES PATENT OFFICE.

LYNN H. SMITH, OF ESCANABA, MICHIGAN.

SOAP-HOLDER.

1,135,857.

Specification of Letters Patent. Patented Apr. 13, 1915.

Application filed April 28, 1914. Serial No. 835,017.

To all whom it may concern:

Be it known that I, LYNN H. SMITH, a citizen of the United States, residing at Escanaba, in the county of Delta and State of Michigan, have invented new and useful Improvements in Soap-Holders, of which the following is a specification.

An object of the invention is to provide a soap holder which can be readily used in connection with a basin or tub and which is adapted to hold the usual cake of soap in such a manner that after the same has been used the water will readily be drained therefrom in order to keep the soap in good condition and prevent the same from becoming soft and unusable.

The invention contemplates, among other features, the provision of a soap holder in the nature of a tray which can be conveniently attached to a wall over a basin or tub and which will hold the soap free from contact with the water and will permit any water on the soap to be readily drained therefrom.

In the further disclosure of the invention reference is to be had to the accompanying drawings, constituting a part of this specification, in which similar characters of reference denote corresponding parts in all the views, and in which:

Figure 1 is a perspective view of the soap holder; Fig. 2 is a vertical transverse sectional view taken through the soap holder, the dotted lines indicating the raised position of the tray; Fig. 3 is a fragmentary horizontal sectional view showing the manner of pivoting the tray in the dish; and Fig. 4 is a fragmentary sectional view taken through one of the stop members, showing the manner of limiting the swinging movement of the tray. Fig. 5 is a sectional view through a portion of the tray.

Referring more particularly to the views, I disclose a soap holder 10 which consists of a dish or receptacle 11 having a supporting back or plate 12 forming a part of the receptacle and preferably provided with a plurality of openings 13, whereby the dish or receptacle can be supported on a wall. The dish 11 is provided with a plurality of vent apertures 14 preferably arranged in rows on the ends of the receptacle and arranged to swing within the receptacle is a tray 15. The tray can be struck or formed from a single piece of material to provide a series of transverse drain channels 16 and

one of the longitudinal edges of the member, preferably the rear edge, terminates in a tubular member 17 in the nature of a hinge member and which has the ends of rivets or pins 18 passing through the dish and secured thereto, extending into the ends of the tubular member whereby the tray 15 will be arranged to swing within the dish or receptacle. Projecting into the receptacle from the front thereof are a plurality of stop members 19 which can also be in the nature of rivets or pins and upon which the front or free end of the tray is adapted to repose in order to hold the tray in spaced relation to the bottom of the dish or receptacle.

A spring-like locking member 20 is secured to the front edge of the tray at its medial portion and is adapted to engage a front edge 21 of the dish or receptacle to hold the tray in locked position in the dish or receptacle, said front edge 21, as well as the side edges 22 of the dish or receptacle, being preferably curved or in the nature of ribs to present a neat and effective appearance, while at the same time the front curved or ribbed edge will afford a convenient means to be engaged by the locking member, said locking member having its free end terminating in a hook 23 which engages the said ribbed edge, as shown and set forth.

Now if it is desired to swing the tray into an open position in order to empty the dish or receptacle from any water that may have accumulated therein or drained from the soap previously supported on the tray, the locking member 20 is disengaged from the front ribbed edge 21 and the tray can then be swung upwardly so that a medial portion of the locking member will engage the upper edge 24 of the back or plate 12, thus holding the tray in raised position so that the water contained in the dish or receptacle can be removed therefrom or the dish or receptacle readily cleaned. To this end the medial portion of the locking member is provided with a notch 25 into which extends a portion of the upper edge 24 when the tray is raised, as mentioned.

From the foregoing description it will be apparent that when the tray is in its lowered position it will be inclined so that the water will readily drain from the soap reposing upon the tray and it will also be seen that the said holder is of a simple

and durable construction and can be easily cleaned and kept in a sanitary condition.

Having thus described my invention, I claim:

- 5 As a new article of manufacture, a soap holder consisting of a single piece of material formed to provide a receptacle and an upstanding back, a portion of which forms a wall of the receptacle, a tray mounted to swing on the body and normally lying wholly within the receptacle, a projection engaged by the free end of the tray to hold the free end of the tray against downward
- 10

movement in the receptacle, and a spring-like latch engaging the front edge of the receptacle to secure the tray in locked position therein, said latch being adapted to engage the upper end of the back when the tray is swung upwardly to lie against the back.

In testimony whereof I affix my signature in presence of two witnesses.

LYNN H. SMITH.
